UNITED STATES PATENT OFFICE.

HOSEA K. KRIEBEL, OF WEST POINT, PENNSYLVANIA, ASSIGNOR OF ONE-HALF TO FRED LIGHT, JR., OF SAME PLACE.

VALVE-GEAR.

SPECIFICATION forming part of Letters Patent No. 290,645, dated December 18, 1883.

Application filed April 25, 1883. (No model.)

To all whom it may concern:

Be it known that I, HOSEA K. KRIEBEL, of West Point, Montgomery county, and State of Pennsylvania, have invented an Improvement 5 in Valve-Gear for Steam-Engines, of which the following is a specification.

My invention has reference to valve-gear for steam-engines; and it consists of an adjustable valve crank-pin made adjustable radially to or 10 from the crank-shaft center by means of a shaft extending through the crank-pin of the engine, which shaft is rotated to change the position of the valve-pin by suitable mechanism, the movement of which is controlled by the speed 15 of the engine, and in many details of construction, all of which is fully set forth in the following specification, and shown in the accompanying drawings, which form part thereof.

The object of my invention is to provide 20 suitable automatic mechanism to that class of steam-engines in which the valve crank-pin is secured to an arm supported by the crank-pin of the engine, and in similar constructions thereto.

In the drawings, Figure 1 is a front elevation 25 of my improved automatic variable cut-off mechanism. Fig. 2 is a rear view of same. Fig. 3 is a sectional elevation of same on line *x x*. Fig. 4 is a modified form of same.

A is the crank-wheel of the engine. B is the 30 shaft. C is the support or bearing. D is the engine crank-pin, and is secured to the crank-wheel A. E is the connecting-rod or piston, the former being used when the cylinder F is stationary, and the latter when it is supposed 35 to be oscillating, the improved valve-gear being adapted to both classes of engines. The crank-pin D is secured rigidly to wheel A, and carries on its outer end an arm, G', to which is pivoted, at *h*, a lever, H, having its upper 40 end slotted, as at *h'*, and its lower end provided with the valve crank-pin I, to which is journaled the valve-rod J. The crank-pin I is set sufficiently out of center to give all the necessary movement to the valve-rod. Working 45 through crank-pin D is a shaft, G, having a crank-pin, *g*, which works in the slot *h'* of lever H. The other end of shaft G on the rear of wheel A is secured to a crank, K, having an arm, K', weighted on its end, as at *k*. Piv- 50 oted at O to the back of wheel A, and diametri- cally opposite to shaft G, is another crank, K,

also carrying an arm, K', having a weight, *k*, and these two cranks K are arranged to point in the same direction, and are connected by a rod or link, M, and pins L. The weights *k* 55 are drawn toward the shaft B by springs N when running at its normal speed. Now, should the speed of the engine increase, the weights swing out by centrifugal force, extending the springs and rotating the shaft G, moving its 60 crank-pin *g*, and also the valve crank-pin I, by its lever H, thus varying the throw of the valve, and automatically varying the point of cut-off by changing its relative position with respect to the crank-pin D, and thereby operates to 65 slow down the engine. The arrows indicate the direction of movement of the various parts.

In Fig. 4 the crank-pin I is carried by a slide, P', which works in a box, P, carried by the arm G', and a rod, n, secured to the slide P', 70 encircled by a spring, N', may be used in place of springs N. The said slide P' is moved in one direction by the lever H and in the other by the spring N'. If desired, both the springs N and N' may be used. The valve crank-pin 75 is preferably made to move in a radial line from the center of the shaft B, so that while the throw of the valve may be greatly varied, the amount of lead or angular advance of the said valve-pin shall remain constant. 80

If desired, the crank K, rod M, and one arm, K', weight *k*, and spring N may be dispensed with; but I prefer the two. I do not limit myself to the construction shown, as it may be modified in various ways without departing 85 from my invention—as, for instance, the crank-pin D may be made to rotate, and thus the shaft G be dispensed with.

I am aware of the patent to Rice, No. 245,017, and claim nothing therein shown or described. 90

Having now described my invention, what I claim as new, and desire to secure by Letters Patent, is—

1. Variable cut-off mechanism for operating valves of steam-engines, which consists of a 95 valve-crank carrying a crank-pin, and supported by the crank of the engine, in combination with means controlled by the varying speed of the engine to automatically change the location of said valve-operating crank, 100 moving it at a radial line to or from the center of the crank-shaft, to vary the time of cut-

off in accordance with demand, substantially as and for the purpose specified.

2. Variable cut-off mechanism for steam-engines, which consists of an engine-crank and its 5 pin, in combination with a valve crank-pin supported by said engine crank-pin, mechanism acting by centrifugal force to vary the position of said valve crank-pin by moving it radially to or from the center of the crank-pin, 10 and connecting mechanism operating through said engine crank-pin to transmit the effect of the centrifugal mechanism to the said valve crank-pin, substantially as and for the purpose specified.

15 3. Variable cut-off mechanism for steam-engines, which consists of an engine-crank and its pin, in combination with a valve crank-pin supported by said engine crank-pin, mechanism acting by centrifugal force to move said 20 valve crank-pin radially toward the crank-shaft center, a spring or springs to move it radially in an opposite direction, connecting mechanism operating through said engine crank-pin to transmit the effect of the centrifugal mechanism, and springs to the said valve 25 crank-pin, substantially as and for the purpose specified.

4. Valve-gear for steam-engines, which consists of crank-wheel A, crank-pin D, supporting the lever H, carrying the valve crank-pin

I, shaft G, having crank-pin g, and mechanism acting by centrifugal force to turn said shaft G independent of its revolution around the shaft of the crank-wheel A, substantially as and for the purpose specified.

35

5. The combination of crank-wheel A, crank-pin D, shaft G, valve crank-pin I, centrifugal mechanism, and connecting mechanism, substantially as described, from said shaft G to said pin I, whereby the latter is moved radially 40 over the face of the crank A to change its relative position with respect to the crank-pin D, substantially as and for the purpose specified.

40

6. The combination of crank-wheel A, crank-pin D, shaft G, having crank-pin g, lever H, 45 having valve crank-pin I, arm K', weight k', and spring N, substantially as and for the purpose specified.

45

7. The combination of crank-wheel A, crank-pin D, shaft G, having crank-pin g, lever H, 50 having valve crank-pin I, cranks K, arms K', weights k, rod or link M, and springs N, substantially as and for the purpose specified.

50

In testimony of which invention I hereunto set my hand.

HOSEA K. KRIEBEL.
